ROOFING UNIT AND ASSEMBLY THEREOF

David E. Gray, Corning, N. Y., assignor to
Corning Glass Works, Corning, N. Y., a corpora-
tion of New York

Application October 19, 1940, Serial No. 361,969

11 Claims. (Cl. 108—10)

This invention relates to roofs and roofing materials, and more particularly to a novel form of tile or fabricated shingle and the roof covering built therewith.

The primary object of the invention is a strong durable roof, which is weather tight, especially economical both of material and labor of installation, and which is also attractive in appearance.

A further object of the invention is a tile, shingle, or roofing unit whose design is such that its assembly with other similar units used in covering a roof leaves the major surface portion of each unit exposed to the weather.

Another object of the invention is a tile, shingle or roofing unit which may be readily anchored to a roof structure without the necessity of resorting to perforating the unit.

A still further object is a tile, shingle, or roofing unit adapted to be anchored to a roof structure in such a fashion that lifting of a unit by the wind is positively prevented. The invention includes among its features a roofing unit having part of its bounding edges bent in one direction at right angles to its adjoining surface portion and with the remaining of its bounding edges bent in the opposite direction in such a fashion that a number of such units can be formed into a roof cover assembly having a coverage very nearly approaching the sum of the combined surface areas of the individual units.

A further feature of the invention is the manner of spacing overlapping parts of the units to prevent leakage by capillary action.

Other features and advantages of the invention will become apparent from a further perusal of the description of the embodiment of the invention illustrated in the accompanying drawing wherein:

Fig. 1 is a plan view of a fragment of a roof covering assembly formed of roofing units of the present invention;

Fig. 2 is a perspective view illustrating the overlapping arrangement of the units.

Fig. 3 is a sectional view taken on line 3—3 of Fig. 1.

In the form of the invention shown each tile unit 10 embodying the invention is a generally flat but somewhat warped square piece of material of a suitable thickness, depending on the material from which the unit is made, although the unit may be shaped otherwise than square if desired. For example, it may be of diamond shape to produce a different ornamental effect. Two of the adjoining bounding edges of the unit have upstanding edges 12 with notches 13 for

15 accommodating clips 23 used to secure the units to a roof structure 21. At the corner 15 where edges 12 join, the upstanding edges are of additional height. The remaining edges 14 of the unit are projected downwardly in the same fashion as edges 12 project upwardly with their adjoining corner 16 projected downwardly a distance corresponding to the additional height of corner 15 adjacent edges 12. The opposite ends 10 of edges 12 and 14 meet at corners 25 and 26 respectively.

In a typical roof structure all of the units are duplicates of the unit 10, except for those bordering the structure. The latter units are composed 15 of those portions of units 10 necessary to substantially evenly parallel the roof edges and may be cut from units 10 or separately fabricated as is most convenient, as such portions of units are of the exact configuration as the corresponding parts as a unit 10. In order to avoid confusion in the detailed description which follows, the different units specifically referred to are given separate identification numerals even though, as above stated, they are identical to one another.

As previously mentioned, the units are anchored to a supporting roof structure 21 by clips 23 one end of each of which clamps over an edge portion 13 of a unit and the other end of 30 which is directly nailed to the roof structure. Since a substantial portion of a unit projects beyond its location of anchorage, raising of the unit is impossible without actually destroying the anchorage; consequently the danger of wind raising the unit is very remote.

In a typical roof structure such as illustrated in Fig. 1, the first horizontal row or course of units laid comprises a unit 18, a number of similar units, of which units 19 are examples, and at the end opposite unit 18 a unit (not shown) similar to unit 18.

The top course on either side of a roof gable, such as shown, comprises a plurality of whole units which are duplicates of the unit 10, overlapped by a ridge cap 24 which simply covers the upper halves of the units and has its free edges preferably bent down into contact with the surfaces of those units.

Those units of the respective intermediate 50 courses include any necessary fractional units, such for example as unit 21, and the required number of whole units comprising duplicates of unit 10.

Assembly of a roof, as is customary, begins with the laying of the first course of units, which

are so laid that their corners 25 and 26 adjoin one another in a horizontal row and are anchored in place by means of a number of the clips 23. Once the first row of units has been properly laid and anchored, laying of the subsequent courses is a relatively simple matter. In the laying of the second course the downwardly projecting corner 16 of each unit 10 is fitted into the apex of the triangular space below the adjoining corners 25-26 and up against the edges 14 of the adjoining units. The corners 16 in occupying the identified spaces between units of the first row function to laterally space the overlapped edges 12 and 14 a predetermined distance from one another, thereby establishing non-capillary gaps 20 between such edges. The units of the second course inherently become arranged in the same relation to one another as are the units of the first course. From the foregoing the manner of laying the subsequent courses will be understood without further explanation. It is to be observed, however, that at the junctions of the corners of the respective units of all intermediate rows or courses relatively large enclosed spaces 28 and 29 are formed within the confines of corners 15 and 16. These spaces serve as temporary reservoirs for water which may, during certain wind conditions, be forced under the edges of the corners 16. The capacities of these reservoirs are such as to prevent danger, were they not provided, of water accumulating at the corners in such volume as to flow over the edges 12 and corners 15 and cause leakage.

With a view to clearing up any further questions as to the relative arrangement of the units with respect to one another special reference is now made to Fig. 2 which illustrates the one upstanding edge 12 of a unit 10¹ as being overlapped by one of the downwardly projecting edges 14 of a unit 10², with the other upstanding edge 12 of unit 10¹ overlapped by a downwardly projecting edge of a unit 10³, and with the upstanding corner 15 of unit 10¹ covered by unit 10 which has its downwardly projecting corner 16 resting on surface of unit 10¹.

I claim:

1. As an article of manufacture, a roofing tile in the shape of a parallelogram comprising a generally flat body portion, upstanding flanges bounding two adjacent sides of said body portion and downwardly extending flanges of similar character bounding the remaining two sides of said body portion, said body portion being so warped that the tops of said upwardly extending flanges at their point of intersection lie substantially in the same plane as diagonally located corners of the body portion.

2. An assembly of roofing tile of parallelogram outline arranged in successive horizontal rows or courses along the breadth of a roof with the tiles of each course so arranged that two of the diagonally disposed corners of each of the tiles are in the same horizontal plane, each tile having oppositely disposed plain surfaces bounded by upstanding edges along the sides above the above identified corners and similarly bounded by downwardly projecting edges along the sides below such corners, the upstanding edges of the tiles of one course being overlapped by the downwardly projecting edges of the tiles of an adjacent course with the edges of the respective tiles meeting the plain surfaces of the tiles overlapped.

3. An assembly of roofing tile of parallelogram outline arranged in successive horizontal rows or

courses along a roof breadth with the tiles of each course so arranged that two diagonally disposed corners of the tiles are in the same horizontal plane, each tile having oppositely disposed plain surfaces bounded by upstanding edges along the sides above the above identified corners and similarly bounded by downwardly projecting edges along the sides below such corners, the downwardly projecting edges of the tiles of one course overlapping the upstanding edges of the tiles of an adjacent course and arranged to meet plain surfaces thereof.

4. An assembly of roofing tile of parallelogram outline arranged in successive horizontal rows or courses along a roof breadth with the tiles of each course so arranged that diagonally disposed corners of the tiles are in the same horizontal plane, each tile having oppositely disposed plain surfaces bounded by upstanding edges along the sides above the above identified corners and similarly bounded by downwardly projecting edges along the sides below such corners, the downwardly projecting edges of the tiles of one course overlapping the upstanding edges of the tiles of an adjacent course and spaced from the upstanding edges which they overlap.

5. A roofing tile assembly composed of tile units of parallelogram outline which are of generally flat configuration as regards their main body portion and which have their bordering edges extended in directions substantially at right angles to their adjacent body portions, said tiles being so arranged with respect to one another that any tile of the assembly surrounded by other tiles thereof has two of its bounding edges lapped over at least part of the bounding edges of three surrounding units in substantially meeting relation with the main body portions thereof and has the remaining of its own bounding edges covered by the bounding edges of three other surrounding units and in substantially meeting relation with their main body portions.

6. A roofing tile assembly composed of tile units of parallelogram outline which are of generally flat configuration as regards their main body portion and which have their bordering edges extended in directions substantially at right angles to their adjacent body portions, said tiles being so arranged with respect to one another that any tile of the assembly surrounded by other tiles has one corner and the adjoining edges thereof lapped over corners of three other units of the assembly and in substantially meeting relation with their main body portions thereof.

7. A roofing tile assembly composed of tile units of parallelogram outline which are of generally flat configuration as regards their main body portion and which have their bordering edges extended in directions substantially at right angles to their adjacent body portions, said tiles being so arranged with respect to one another that any tile of the assembly surrounded by other tiles has one corner and the adjoining edges thereof lapped over corners of three other units of the assembly and has another corner thereof covered by a corner of another unit of the assembly with the edges of such corners in substantially meeting relation with the main body portions of the tiles they overlap.

8. A roofing tile assembly composed of tile units of generally flat configuration as regards their main body portion and which are of such outline configuration as to have at least three corners and connecting bordering edges extended in directions substantially at right angles to their

adjacent body portions, said tiles being so arranged with respect to one another that any tile of the assembly surrounded by other tiles has one edge thereof lapped over corners of three other units of the assembly, another corner thereof covered by a corner of another unit of the assembly and a third covered by one of the edges of a still further unit of the assembly the edges of each unit being arranged in substantially meeting relation with the main body portions of the units they overlap.

9. In an assembly of roofing tile, a plurality of tile each of which has two of its adjoining edges upstanding with respect to its major surface area and which has two edges projecting downward with respect to such area, clips overlapping limited portions of the upstanding edges of the tiles securing them to roof boards or the like, and certain tiles of the assembly so arranged with respect to others of the assembly as to have their downwardly projecting edges overlapping upstanding edges of a plurality of the other tiles of the assembly. 20

10. In a roof structure, roofing units each having down-turned edges and upturned edges with the down-turned edges of the respective units lapped over the upturned edges of other of the units, the said units also having upturned and down-turned corner portions cooperative with the overlapped edges of the respective units to space the edges of the overlapped units a predetermined distance from one another.

11. As an article of manufacture, a roofing tile with a relatively flat surfaced body portion having two adjoining edges in the form of flanges upstanding with respect to the surfaces of the body portion, said flanges being of different height required to bring them in meeting relation with surfaces of body portions of similar tiles arranged at different levels with respect thereto when grouped in cooperative relation to form a roof assembly. 15
